UNITED STATES PATENT OFFICE.

ANDREW W. GRAHAM, OF BUFFALO, NEW YORK, ASSIGNOR OF ONE-HALF TO ELLIS M. TREAT, OF PITTSBURGH, PENNSYLVANIA.

SEPULCHRAL MEMORIAL.

1,203,534.

Specification of Letters Patent. Patented Oct. 31, 1916.

Application filed March 13, 1916. Serial No. 83,924.

To all whom it may concern:

Be it known that I, ANDREW W. GRAHAM, a citizen of the United States, residing at Buffalo, in the county of Erie and State of New York, have invented certain new and useful Improvements in Sepulchral Memorials, of which the following is a specification.

This invention relates to sepulchral memorials, and refers more especially to that class of structures described and claimed in Letters Patent No. 1,167,291, granted to me, Jan. 4, 1916.

An object of this invention is to produce a memorial positioned above the ground and provided with a novel form of entrance closure to the said memorial.

Another object of this invention is to provide a memorial in which the entrance closure constitutes one of the side walls 20 thereof.

Another object of this invention is to provide an entrance closure for a memorial comprising separable sections pivotally mounted at the corners thereof and adapted 25 to swing inwardly against the walls of the memorial chamber.

A further object of this invention is to produce a memorial, the entrance closure of which is formed flush with the side wall 30 thereof and prevents the admission of water and other foreign extraneous substances which would tend to deteriorate the structure.

The invention further consists in the 35 novel elevating means for the respective separable hinged sections whereby the closures can be elevated to clear the abutting flange at the base of the memorial and then swung inwardly as will more fully herein- 40 after appear.

With these and other objects in view, the invention further consists in the novel arrangement and combination of parts herein- 45 after described and pointed out in the ap- pended claims.

Referring to the drawings which show by way of illustration an embodiment of this invention, Figure 1 is a horizontal sectional plan view through a sepulchral memorial, and Fig. 2 is a front elevation of a memo- 50 rial, the respective hinged entrance closures and the mechanism for elevating the same being shown in section.

In the production of memorials, it has been found advantageous to produce a 55 monumental effect, and the present mechanism for gaining access to the said memorial has been concealed within the memorial so as to maintain all of the monumental and artistic embellishments and configurations. To that end the present invention has been designed and comprises a hollow memorial 1 provided with rear wall 2, end walls 3, 4, and a front or entrance closure 5. This memorial may be constructed 60 of such monumental material as may be found most desirable and preferably comprises a base 6 and intermediate section 7 which includes the walls, and the cap or top 8. The size and general design of this memorial may be varied and modified and I do not limit myself to the exact illustration 70 set forth herein.

The entrance closure to the said memorial 75 comprises oppositely arranged door-sections 9 and 10 and an intermediate or supplemental door section 11 interposed therebetween. This intermediate door section consists preferably of a metal frame 12 having such artistic glass or transparent decorations 13 thereon, as may be desired. This intermediate door section is hinged at 14 to one of the oppositely arranged door sections hereinbefore referred to, and is movable therewith. When the entrance closure is in 80 the position shown in full lines in Fig. 1, the intermediate door section 11 is in alignment with the respective door sections 9 and 10 and is designed to snugly engage the ends of the said oppositely arranged sections. The oppositely arranged doors 9 and 10 are pivotally mounted on vertical pintles or shafts 15, 16. These shafts are suitably 85 journaled in upper and lower bearings 17 and 18, respectively, as shown in Fig. 2. 90 Suitable recesses 19 are provided in the respective door sections 9 and 10 at the pivotal ends thereof and are adapted to receive bearing and supporting plates 20. These plates are provided with tubular internally 100 threaded extensions 21 through which the threaded portions 22 of the vertical shafts 15 and 16 pass. The door sections are cut away as at 23 so as to provide access for suitable rod-engaging means for elevating 105 the respective doors, the operation of which

will now be described. The elevating mechanism comprises the pivotal shafts 15 and 16, the screw threaded portions provided thereon and holes 24 provided in said shaft 5 to receive an operating or turning bar as will be readily understood.

In operation, it will be seen that upon turning the respective shafts 15 and 16, by the insertion of the bar in the holes 24 the 10 door sections 9 and 10 will be elevated. A recess 25 is provided on the underside of the cap piece 8 to receive the respective door sections when they are elevated. This elevation of the door will be sufficient to clear 15 the floor and permit the respective door sections to swing inwardly. These doors when in closed position are normally lower than the floor section of the memorial to prevent the admission of water and the beating in of other material. When the doors have been elevated to the level of the floor, they can be swung back as shown in dotted lines in Fig. 1 and be positioned against the 20 respective walls 2, 3 and 4 of the respective 25 memorial.

From the foregoing, it will be seen that I have provided a sepulchral memorial, the monumental design of which can be adhered to and at the same time ready entrance 30 thereto can be secured.

It is obvious that certain minor changes may be made in the form and construction as well as the ornamentation of the invention without departing from the material 35 principles involved.

Suitable casket lowering mechanism can be provided in the said memorial, and other compartments beneath the ground for the reception of the caskets can be used in connection with this memorial as will be readily understood.

Having thus described my invention, what

I claim and desire to secure by Letters Patent is:—

1. In a sepulchral memorial provided with an entrance opening including a rabbeted sill, a closure for the opening arranged to seat in the rabbet, pivot means constituting a hinge for the closure, and coacting means carried by the pivot and closure and arranged to primarily raise the closure from the rabbet to permit swinging of said closure.

2. In a sepulchral memorial provided with swinging access means, said access means being movable vertically into operative and inoperative positions, a pivot, and coacting means carried by the access means and pivot and arranged to effect vertical movement of said access means.

3. In a sepulchral memorial, a swinging closure, pivot means constituting a hinge for the closure, said pivot means being arranged to rotate at times independently of the closure and at times with the closure, and coacting elements carried by the closure and pivot means and arranged to effect movement of the closure longitudinally of the pivot means upon independent rotation of the latter.

4. In a sepulchral memorial having a closure, a nut carried by the closure, and a pivot rod for the closure and rotatable independently of said closure, said pivot rod having a threaded portion engaging the nut 75 and being provided with means for the connection of an operating device.

In testimony whereof I affix my signature in presence of two witnesses.

ANDREW W. GRAHAM.
